CLAIM

The ornamental design for eye protector, as shown and described.

DESCRIPTION

FIG. 1 shows a top, left sided perspective view of a first embodiment of an eye protector showing my new design;

FIG. 2 shows a top view thereof;

FIG. 3 shows a bottom view thereof;

FIG. 4 shows a front view thereof;

FIG. 5 shows a rear view thereof;

FIG. 6 shows a left sided view thereof;

FIG. 7 shows a right sided view thereof.

FIG. 8 shows a top, left sided perspective view of a second embodiment of an eye protector showing my new design;

FIG. 9 shows a top view thereof;

FIG. 10 shows a bottom view thereof;

FIG. 11 shows a front view thereof;

FIG. 12 shows a rear view thereof;

FIG. 13 shows a left sided view thereof;

FIG. 14 shows a right sided view thereof.

FIG. 15 shows a top, left sided perspective view of a third embodiment of an eye protector showing my new design;

FIG. 16 shows a top view thereof;

FIG. 17 shows a bottom view thereof;

FIG. 18 shows a front view thereof;

FIG. 19 shows a rear view thereof;

FIG. 20 shows a left sided view thereof; and,

FIG. 21 shows a right sided view thereof.
